UNITED STATES PATENT OFFICE

2,656,688

REFRIGERATOR DOOR WITH A COMPARTMENT

Lester H. Hinkel, Evansville, Ind., assignor to International Harvester Company, a corporation of New Jersey

Application October 15, 1951, Serial No. 251,337

9 Claims. (Cl. 62—99)

1

This invention relates generally to a refrigerator door and more particularly to a refrigerator door which is provided with a removable container.

The most common type of refrigerator cabinet which is used for domestic purposes is the upright cabinet type having a front vertically hinged door. The food storage compartment of the cabinet is generally provided with horizontal shelves on which the food articles may be placed and access to the food compartment is readily available upon opening of the door. The door of the average household refrigerator is opened many times during a day and each of these openings causes a substantial portion of the cold air within the refrigerated compartment to spill out into the room and to be replaced by warm moist room air. This causes the refrigeration system to operate more frequently in order to maintain the food storage compartment within a desired temperature range. The moisture from the room air collects and freezes on the evaporator so that the efficiency of the refrigeration system is reduced and more frequent defrosting of the evaporator is required. To overcome these disadvantages, the present invention provides a refrigerator cabinet having a door which is provided with means for removing food articles from the cabinet without the necessity of opening the door.

One object of the present invention is to provide a refrigerator door with a container which is adapted to be removed from the cabinet while the door is in closed position.

Another object of the present invention is to provide a refrigerator door with a removable container which is adapted to be loaded in the evening with food articles necessary for preparing a breakfast, then removed from the door and placed on a stove during the preparation of breakfast.

Another object of the present invention is to provide a refrigerator door with a removable container which will be maintained at a higher temperature than the food storage compartment of the refrigerator so that it will be suitable for the storage of certain food articles, such as butter.

Another object of the invention is to provide the upper portion of a refrigerator door with a front opening into which a container is adapted to be positioned.

Another object of the invention is to provide a frame member which closes and seals a joint between the inner door liner and outer door pan around the opening and which also supports the container.

Another object of the invention is to provide the bottom of the container with a groove which

2

engages a horizontal rib of the frame, and to provide a top portion of the container with a latch which engages the frame.

Another object of the invention is to provide the inner liner with projecting fins which contact a gasket on the refrigerator evaporator and serve as an evaporator door and allow the cold air within the evaporator to be in direct contact with the inner liner adjacent to the container.

Other objects and advantages of the invention will be apparent to those skilled in the art from a reading of the following description in conjunction with the drawings attached hereto and forming a part hereof in which:

Fig. 1 is a front elevational view of the top portion of a refrigerator cabinet.

Fig. 2 is a horizontal sectional view taken along line 2—2 of Fig. 1.

Fig. 3 is an enlarged vertical sectional view taken along line 3—3 of Fig. 1.

Fig. 4 is a rear elevational view of the frame which is shown in section in Figs. 2 and 3.

Fig. 5 is a rear perspective view of the container which is shown in section in Figs. 2 and 3.

For a more detailed description of the invention, reference is made to the drawings in which the top portion of a refrigerator cabinet 10 is shown in Fig. 1. The cabinet comprises spaced apart walls 11 and 12 having insulating material 13 disposed therebetween. The cabinet 10 encloses a food storage compartment or chamber 14 and a refrigerant evaporator 15 is secured in the upper portion of the chamber. A vertically hung door 16 is secured to the cabinet 10 by hinges 17 and is provided with a handle 64. By manually pulling on handle 64, the door may be unlatched and rotated around hinges 17 whereby access to chamber 14 is provided.

The door 16 comprises an outer door pan 18 having inturned edge portions to which an inner door liner 19 and a sealing gasket 20 are secured by suitable clips 21. The space between the outer pan 18 and inner liner 19 is filled with an insulating material 22 so that when the door is in closed position the food storage compartment 14 is effectively insulated. The upper portion of the outer pan 18 is provided with a front opening 23 and is bent inwardly around the opening into a flange 24 having an inturned edge portion 25 bent at substantially right angles thereto. The inner liner 19 is provided with a horizontal top wall 26, a horizontal bottom wall 27 and vertical side walls 28 and 29 which all extend toward the outer door pan 18 and terminate in close proximity to the flange 24. These walls enclose a container compartment 38 therebetween which is void of insulating material.

A rectangular shaped frame 30, having cylindrical shaped projections 31 spaced along one

side, is positioned adjacent the inturned edge portion 25 of flange 24. The frame is provided with an inturned portion 32 which overlaps the walls 26, 27, 28, and 29 of the inner liner 19. The lower portion of frame 30 is provided with a semi-circular shaped horizontally extending rib 33, and an upper portion of the frame is provided with a downwardly extending projection or catch 34. A rubber gasket 35 fits over the outer edge of the frame 30. The inturned edge portion 25 of flange 24 is provided with spaced apart apertures through which the projections 31 extend. Suitable clips 36 fasten over projections 31 and secure the frame 30 to flange 24 with the rubber gasket 35 held tightly therebetween. A sealing material 37 is disposed between the frame 30 and walls 26, 27, 28, and 29 of the inner liner 19 in order to seal the container compartment 38 from the insulation space of the door 16.

Removably secured within compartment 38 is a drawer or container 39 having a front wall 40 and an inner wall 41 which are spaced apart with insulating material 42 disposed therebetween. The edges of the front wall 40 and inner wall 41 are secured together in any suitable manner. Inner wall 41 is provided with a lower shelf 43 and upper shelf 44 which are fashioned with common end walls 45 and 46. Front wall 40 is provided with a recessed portion 47 and a vertical handle 48 which may be grasped by an operator to aid in moving the container 39. A lower portion of inner wall 41 is provided with a horizontal groove 49 which is adapted to engage the horizontal rib 33 of frame 30. Positioned between outer wall 40 and inner wall 41 is a latch 50 having a plunger 51 which extends through a slot 52 in inner wall 41 and engages the catch 34 of frame 30. Rod 53 extends from latch 50 through outer wall 40 and is provided with knob 54 which is located above handle 48. Rod 53 is connected to plunger 51 in such a manner that when knob 54 is pushed inwardly, plunger 51 will be moved downwardly out of engagement with catch 34.

The front edge of evaporator 15 is provided with an outwardly turned flange 55 to which a rubber gasket 56 is secured by clips 57. The inner surface of inner liner 19 is provided with inwardly extending baffles 58, 59, 60, and 61. As best seen in Fig. 3, the inner edge of each baffle engages gasket 56 of evaporator 15 when the door 16 is closed so that the interior of the evaporator is sealed from the food storage chamber 14. The chamber 62 which is enclosed by evaporator 15 will be maintained at a lower temperature than the food storage chamber 14 and is usually termed the low temperature or freezer compartment or chamber. It is customary to insulate the freezer chamber of a refrigerator cabinet from the food storage chamber by providing an evaporator door for covering the open front of the evaporator. In the present invention the freezer chamber 62 is sealed from the food storage chamber 14 by the baffles 58, 59, 60, and 61 so that a separate door is not required. Inner liner 19 is preferably constructed from plastic or other insulating material and the rectangular portion 63 which is surrounded by baffles 58, 59, 60, and 61 is constructed a predetermined thickness or provided with insulating material, so that the container compartment 38 will be cooled to a proper temperature by the transfer of heat through the inner liner 19.

When it is desired to remove container 39 from the door 16, knob 54 may be pushed inwardly in order to lower plunger 51 below catch 34. By 75

grasping handle 48 the container 39 may be lifted or tilted so that groove 49 is raised above rib 33, then pulled out of compartment 38. As seen in Fig. 5, the shelves 43 and 44 of the container 39 are readily available for receiving food articles. After the food articles are inserted thereon, the container 39 may be returned to compartment 38 and pushed inwardly to closed position where groove 49 engages rib 33 and plunger 51 engages catch 34 as shown in Fig. 3. Inner wall 41 of the container contacts gasket 35 and seals thereagainst so that compartment 38 is sealed from the outside air. The cold air within freezing chamber 62 contacts rectangular portion 63 of inner liner 19 adjacent container compartment 38 so that the temperature within compartment 38 will be maintained within a desired range. It is contemplated that compartment 38 be maintained at a higher temperature than food storage chamber 14 in order that it be particularly adapted for the storage of the essential items for preparing a breakfast such as eggs, bacon, fruit juice, cream, jam, and butter. The container 39 may be loaded with the food items in the evening and then removed from the refrigerator and placed on or near a stove during the breakfast preparation. Because of the higher temperature of compartment 38, the eggs will be in a better condition for cooking, the strips of bacon can be more easily pulled apart, and the butter and jam will be in better condition for spreading than if they were maintained at the lower temperature of food storage 14.

From the foregoing description it will be apparent that a removable container is provided for a refrigerator which will be useful for the storage of food articles. A container of this type will permit the removal of food articles stored therein without the necessity of opening the refrigerator door whereby the cold dry air within the refrigerator will not be replaced by the warm moist room air so frequently. This will decrease the amount of frost accumulation on the evaporator and reduce the running time of the motor-compressor of the refrigeration system. By constructing the rectangular portion 63 of inner liner 19 a predetermined thickness, the temperature of the container compartment 38 will be maintained at a desired temperature.

Although the present invention has been described in conjunction with a preferred embodiment, it will be readily understood by those skilled in the art that modifications and variations may be resorted to without departing from the spirit of the invention or from the scope of the appended claims.

What is claimed is:

1. A refrigerator comprising a cabinet having a food storage chamber which is provided with a door opening, a door movable to open and close said door opening, said door having a compartment therein and being provided with a front opening which furnishes access into said compartment, a container slidably secured in said compartment and being adapted to be moved through said front opening, said container being provided with shelves for the storage of food articles, and said container having a front wall which closes said front opening.

2. A refrigerator comprising a cabinet having a food storage chamber which is provided with a door opening, a door movable to open and close said door opening, said door comprising an outer door pan and an inner liner with insulating material therebetween, an evaporator secured within

said chamber with the walls thereof enclosing a freezing chamber, said inner liner being provided with baffles which contact the inner edges of said walls and close said freezing chamber from said storage chamber when said door is in closed position, and a recessed portion provided within said insulating material between said outer pan and said inner liner adjacent to said baffles whereby the recessed portion will be cooled by the transfer of heat through said inner liner.

3. A refrigerator comprising a cabinet having a food storage chamber which is provided with a door opening, a door movable to open and close said door opening, said door comprising an outer door pan and an inner liner with insulating material therebetween, an evaporator secured within said chamber with the walls thereof enclosing a freezing chamber, said inner liner being provided with baffles which contact the inner edges of said walls and close said freezing chamber from said storage chamber when said door is in closed position, a recessed portion provided within said insulating material between said outer pan and said inner liner adjacent to said baffles whereby the recessed portion will be cooled by the transfer of heat through said inner liner, said outer pan being provided with a front opening which communicates with said recessed portion, and means for closing and sealing said front opening.

4. A refrigerator comprising a cabinet having a food storage chamber which is provided with a door opening, a door movable to open and close said door opening, said door comprising an outer door pan and an inner liner with insulating material therebetween, an evaporator secured within said chamber with the walls thereof enclosing a freezing chamber, said inner liner being provided with baffles which contact the inner edges of said walls and close said freezing chamber from said storage chamber when said door is in closed position, a recessed portion provided within said insulating material between said outer pan and said inner liner adjacent to said baffles whereby the recessed portion will be cooled by the transfer of heat through said inner liner, said outer pan being provided with a front opening which communicates with said recessed portion, and a container movably secured within said recessed portion, said container adapted to be moved through said front opening.

5. A refrigerator comprising a cabinet having a food storage chamber which is provided with a door opening, a door movable to open and close said door opening, said door comprising an outer pan and an inner liner with insulating material therebetween, an evaporator secured within said chamber with the walls thereof enclosing a freezing chamber, one side of said inner liner being provided with baffles which contact the inner edges of said walls and close said freezing chamber from said storage chamber when said door is in closed position, the opposite side of said inner liner being provided with wall members which are in alignment with said baffles and extend toward said outer pan, said wall members enclosing a compartment which is cooled by the transfer of heat through said inner liner.

6. In a refrigerator comprising a cabinet having a food storage chamber which is provided with a door opening, a door movable to open and close said door opening, said door comprising an outer pan and an inner liner with insulating material therebetween, said inner liner formed of a plastic material, a portion of said inner liner being formed with wall members thereon which

extend toward said outer pan and enclose a compartment therebetween, said outer pan being provided with a front opening and an inturned flange therearound which extends inwardly toward said wall members, and a frame member connecting said flange and said wall members in sealed relationship.

7. A refrigerator comprising a cabinet having a food storage chamber which is provided with a door opening, a door movable to open and close said door opening, said door comprising an outer pan and an inner liner with insulating material therebetween, said inner liner being provided with wall members which extend toward said outer pan and enclose a compartment therebetween, said outer pan being provided with a front opening and an inturned flange therearound which extends inwardly toward said wall members, a frame member connecting said flange and said wall members in sealed relationship, and a container movably secured within said compartment and being adapted to be moved through said front opening.

8. A refrigerator comprising a cabinet having a food storage chamber which is provided with a door opening, a door movable to open and close said door opening, said door comprising an outer pan and an inner liner with insulating material therebetween, said inner liner being provided with wall members which extend toward said outer pan and enclose a compartment therebetween, said outer pan being provided with a front opening and an inturned flange therearound which extends inwardly toward said wall members, a frame member connecting said flange and said wall members in sealed relationship, said frame being provided with a raised portion, and a container movably secured within said compartment and being adapted to be moved through said front opening, said container being provided with a recessed portion which engages said raised portion when in closed position.

9. In a refrigerator cabinet construction having a food storage compartment and having an open ended freezer compartment disposed within said food storage compartment, and having an outer cabinet door panel containing an opening therein in alignment with said open ended freezer compartment, an inner panel for said cabinet door formed of a plastic material, said inner door panel formed with baffles thereon which will seal said open ended freezer compartment from said food storage compartment when said inner door panel is mounted to cooperate with said outer cabinet door panel, said inner door panel further formed with wall members thereon on the side thereof opposite from the side having said baffles thereon and in alignment with said baffles so that said inner door panel forms a door compartment, when said inner door panel is mounted to cooperate with said outer cabinet door panel, which will be cooled by heat passing through said door panel adjacent to said freezer compartment.

LESTER H. HINKEL.
